ARTHUR C. GAYNOR, OF STRATFORD, CONNECTICUT

ELECTRIC SWITCH

Application filed November 25, 1930, Serial No. 498,004.

This invention relates to electric switches, and more particularly, to a switch and switch-actuating mechanism for use with power driven tools.

In certain power driven tools, floor scrapers for example, the tool should be under the control of the operator so long as the motor is being driven, otherwise the tool or appliance may get out of control and cause considerable damage to be done to the work, a floor, for instance, or adjacent objects such as the walls, fixtures or the like. The workmen are instructed in this regard, yet it has frequently occurred that the operator, instead of throwing "off" a switch carried by the tool, pulled out the attachment plug at the end of the table supplying current to the tool to stop the motor, and subsequently reinserted the attachment plug without holding the tool with the result that the motor would drive the tool and cause the damage stated.

An object of this invention is to provide a switch and tool handle mechanism which is so organized that the moment the operator's grip is released, the switch is turned "off", thus stopping the motor, and requiring the presence of the operator's hand upon the tool to start the motor.

In the specific form of this invention illustrated herein, this is accomplished by providing a rotating handle on the tool and connecting this handle to the switch mechanism, the spring of which normally tends to move the handle in one direction, that is in "off" direction. In this arrangement to throw the switch "on", the handle must be turned by the operator and the moment that the grip is released the handle and switch mechanism will cause the switch to be thrown "off".

A particularly important and advantageous feature of this invention is the arrangement of the parts so that while full movement of the handle is required to throw the switch "on", the extent of the ordinary movements of the handle incident to the manipulation of the tool by the workman will not throw the switch "off", but it will only be thrown "off" when the grip on the handle is completely released. Thus, the operator may use the tool without being constantly mind-

ful of the position of the handle or the switch mechanism so long as the grip on the handle is maintained, and, as stated above, the motor will be rendered inoperative immediately upon the release of the operator's grip on the handle.

Other features and advantages will hereinafter appear.

In the accompanying drawings illustrating one form of my invention, that at present preferred—

Figure 1 is a top plan view of the handle portion of the floor scraper showing the switch mechanism of the present invention applied thereto, the cover plate for the casting for the switch being broken away to show underlying parts.

Fig. 2 is a longitudinal sectional view through the switch proper showing the means for normally urging the switch to circuit opening position and the yoke for supporting the switch.

Fig. 3 is a longitudinal sectional view taken through the tool handle and switch actuating mechanism and showing the latter in "off" position, that is in position where the operator's hand is not gripping the handle.

Fig. 4 is a similar view showing the actuating mechanism in the position to which it is moved to throw the switch "on".

Fig. 5 is a similar view which shows by comparison with Fig. 4 the amount of oscillation which the hand grip may have before the switch has moved sufficiently to cause it to open the motor circuit.

The tool handle shown in the accompanying drawings by way of example is attached to a rod or pipe 10, the other end of which is connected to a motor driven machine such, for instance, as a floor scraper. It has a neck 11 threaded to receive the rod or pipe 10 and a housing 12 for the switch. At the side opposite the neck 11, the switch housing 12 has a pair of arms 13 in which there is supported a hand grip 14. This hand grip 14 is usually rotatably mounted on a rod 15 so that the movements of the operator's hand in the vertical plane while encircling the grip 14 may occur without chafing the operator's hand. The tool is propelled for

wardly and backwardly by force exerted by the operator's hand engaging the grip 14 and it is kept from swinging and is steered by a bar 16 extended at right angles from the pipe 10 and having a hand grip 17 on its extremity. In using the tool, the hand engaging the grip 17 does most of the work while the hand engaging the grip 14, as stated, steadies the tool and assists in propelling it forwardly and backwardly.

The hand engaging the grip 17 may be released completely from the handle without disastrous results. However, should both hands be released from the grips 14 and 17 while the motor driven tool is operated, the scrapers or other means employed would offer such resistance that the motor in effect would turn the machine rather than turn the scrapers with the result that the handle and pipe 10 might be thrown about promiscuously, damaging adjacent walls, furniture and fixtures if not actually doing bodily injury to the workmen or other persons in the vicinity.

Heretofore, a manually operated snap switch or the like was provided in the housing 12 to be manipulated by the operator to close and open the circuit to the motor when starting and stopping the use of the tool.

Workmen using the tool are instructed to throw the switch "off" when finishing with the tool, but in spite of these instructions through thoughtlessness or otherwise, the workmen have from time to time merely pulled the plug 18, attached to the cable 19 and entering the housing 12 through an opening 20 in its lower portion, out of the receptacle from which current is being supplied to the tool. This, of course, could be done before both hands were taken from the tool and thus no accident would occur during the disconnection of the tool from the source of current. However, when moving the tool to another part of the room to begin work at that place, not infrequently a workman would insert the attachment plug 18 into the other receptacle without first taking hold of the handle of the tool and hence as soon as the motor started the handle and pipe 10 would spin around and cause damage and possible injury as above stated.

Such improper and dangerous performance of the work has been avoided by the present invention by providing means on the handle for moving the switch to circuit-closing position and automatic means for returning the switch to open-circuit position when the operator's grip on the tool is released.

Heretofore, switch mechanisms have been provided wherein an auxiliary handle must be maintained gripped toward the main handle by the operator to keep the circuit closed, but such devices requiring power to maintain them operated, quickly tire the

finger and hand muscles of the operator and thus unduly fatigue the workman. Besides this, and due to the fatigue produced by its use, such auxiliary grips may be and have on occasion been tied down by a cord or wire by the workman, thus defeating their very purpose.

With the device of the present invention, the effort required to maintain the switch in circuit-closing position is negligible and does not depend upon the muscles of the operator's fingers but merely the presence of his hand on the grip. In addition, it cannot be readily rendered inoperative or have its purpose defeated by the means available to the ordinary workman.

In the drawings illustrating my invention, I have shown the switch as a snap switch, see Fig. 2, having a base 21 and cap 22 held together and attached to a yoke 23 by screws 24, the yoke 23 having horizontal lugs 25 resting on shoulders 26 in the switch housing 12 and held in place by screws 27 threaded in the housing 12 which also serve to hold the cover plate 28 in operative position.

The switch comprises oppositely disposed contacts 29, one pair of which is connected to wires 30 supplying current to the device and the other pair of which is connected to wires 31 leading to the motor. These contacts may be of the type disclosed and claimed in my copending application Serial No. 452,545, filed May 15, 1930. The switch is normally biased so that a switch blade 32, shown in dotted lines in Fig. 2, is disengaged from the contacts 29 to keep the circuit open. This switch blade, which may be of the type disclosed in my Reissue Patent No. 18,385, dated March 15, 1932, is mounted on a crank 33 fulcrumed in a frame 34 and supporting the lower end of a spring 35. The upper end of the spring is engaged by an actuating arm 36 carried by a handle 37 fulcrumed at 38. The mechanism for throwing the switch blade from one to another position is more completely described, and may be of the type disclosed, in my Patent No. 1,852,772, dated April 5, 1932. In the normal hand operation of a switch of this kind, it is thrown "on" and "off" by manipulating the handle 37 which causes the actuator 36 to carry the spring 35 across the axis of oscillation of the crank 33 so that the lower end of the spring will throw the crank to the new position. This handle may be of the type disclosed in my copending application Serial No. 276,886, filed May 11, 1928. In a switch of this kind, considerable movement of the handle 37 may be effected before the spring is carried across the axis of oscillation of the crank and this characteristic of snap switches is taken advantage of to further augment the freedom of movement of the tool grip which controls the switch without causing the circuit to be thrown open, as will hereinafter appear.

The actuator 36 and handle 37 are normally urged to circuit-opening position, that shown in Fig. 2, by a spring 39 having a ball 40 resting in a recess 41 in the handle, similar to the mechanism disclosed in my copending application Serial No. 403,437, filed October 30, 1929. For the sole purpose of actuating the switch, the spring 39 may be slightly more powerful than the spring 35. However, since the spring 39, according to the present invention, has other functions, it is made more powerful than it would need to be solely to actuate the switch. The handle 37 of the switch comprises a bar constituting in effect a first-class lever with the arms 42 and 43 thereof horizontal and as shown in these arms 42 and 43 are angularly disposed so that one of the arms protrudes upwardly while the other is parallel to the base 21.

To actuate this switch so that the blade 32 moves into engagement with the contacts 29 and so that this may be done without fatiguing the operator, there is provided by the present invention a bar 44 extending substantially parallel with the pipe 10 and having at one end a pin 45 extending into a hole 46 in the housing 12 by means of which it is fulcrumed. This bar 44 overlies the arm 43 of the switch handle 37 and extends out of the housing 12 through an opening 47 and from that point extends to the hand grip 14. It may do this in any suitable way. As shown, the bar 44 is provided with a cross piece 48 having rearwardly extending arms 49 lying within and quite close to the arms 13 which carry the grip 14. At their rear ends the arms 49 extend into apertures 50 at the ends of the hand grip 14. These arms 49 and apertures 50 are so shaped that when the hand grip 14 is disengaged by the operator's hand the spring 39 in the switch raises the end 43 of the handle 37 and this lifts the bar 44 so that the extreme ends 51 of the arms 49 rotate the hand grip 14.

When the workman desires to use the machine, the hand grip is grasped at a point lower than would be customary and as the hand is raised the grip 14 is turned so that the walls 52 of the apertures 50 cam the arms 49 downwardly to the position shown in Fig. 4, during which operation the bar 44 depresses the arm 43 of the switch and shifts the spring 35 causing the blade 32 to close the motor circuit through the wires 31. This operation was of course performed against the tension of the springs 35 and 39. However, once the spring 35 has been moved over the axis of oscillation of the crank, it does not react with any tendencies to raise the bar 44 or turn the handle backwardly, that is clockwise as shown in Fig. 4.

Having thus started the motor, the operator proceeds to perform the work desired with the machine and in doing so he need not exercise any caution as to the extent of move-

ment of the grip 14 which occurs due to the movements of his wrist in propelling the machine back and forth, for the handle may move, in the form of the invention herein disclosed, approximately 90° from the position shown in Fig. 4 to the position shown in Fig. 5 before the handle 37 of the switch has rocked far enough to carry the spring 35 across the axis of oscillation of the crank. This freedom of 90° of movement of the grip 14 has been found in practice sufficient to accommodate all natural movements of the operator's hand in manipulating the tool.

The spring 39 and the leverage of the bar 44 and arms 49 thereof, is such that practically no effort is required to rotate the grip 14 or to maintain it in any position to which it may be rotated. It will be seen that so long as the operator's hand engages the grip 14 the switch will be kept "on" whether or not the operator's fingers tightly hold the grip, and that as soon as the operator's hand is removed from the grip 14, the spring 39 will rotate the grip 14, return the bar 44, and cause the handle 37 of the switch to move to circuit-opening position.

The ends 51 of the arms 49 and the apertures 50 in the grip 14 are so related that the grip can neither be swung clockwise nor counterclockwise sufficiently to permit the ends 51 to completely disengage the apertures 50. Hence, in assembling the switch, the bar 44 is first inserted through the hole 47 in the housing 12, then the ends 51 of the arms 49 are inserted in the apertures 50 and finally the rod 15 on which the handle is fulcrumed is inserted through aligned apertures in the arms 13 and the grip 14, the rod being held in place by ends 53.

Variations and modifications may be made within the scope of this invention and portions of the improvements may be used without others.

Having thus described the invention, what is claimed as new and for which it is desired to obtain Letters-Patent, is:—

1. In combination with a tool handle, a hand-grip mounted for rotary movement; an electric switch; and means interconnecting the hand-grip and electric switch for actuation either one by the other.
2. In combination with a tool handle, a hand-grip mounted for rotary movement; an electric switch normally biased to move in one direction; and means connecting the hand-grip to the electric switch for operation of the latter by the former and for the return of the hand-grip to normal position by the switch when the hand-grip is released.
3. In combination with a tool handle, a hand-grip mounted for rotary movement; an electric switch having an actuating means and means for normally urging the actuating mechanism to circuit-opening position; and means interconnecting the hand-grip and

65 exercise any caution as to the extent of move-

- actuating mechanism of the switch for operation of the latter by the former when turned by hand to move the actuating mechanism to cause the circuit controlled by the switch to be closed.
4. In combination with a tool handle, a hand-grip mounted for rotary movement; an electric switch having an actuating means and means for normally urging the actuating mechanism to circuit-opening position; and means interconnecting the hand-grip and actuating mechanism of the switch for operation of the latter by the former when turned by hand to move the actuating mechanism to cause the circuit controlled by the switch to be closed, and for returning the hand-grip to initial position when the operator's hand releases the hand-grip.
5. In combination with a tool handle, a tool-directing hand-grip mounted for turning movement within limits; and means including a snap switch actuated by the hand-grip at limits of its turning movements to open and close a circuit of the tool.
6. In combination with a tool handle, a tool-directing hand-grip mounted for turning movement within limits; and means including a snap switch actuated by the hand-grip at one limit of its turning movement to close a circuit of the tool.
7. In combination with a tool handle, a tool-directing hand-grip mounted for turning movement within limits; and means including a snap switch actuated by the hand-grip at one limit of its turning movement to close a circuit of the tool, the snap switch remaining in circuit-closing position during substantially the entire return movement of the handle.
8. In combination with a tool handle, a tool-directing hand-grip mounted for turning movement within limits; and means including a snap switch actuated by the hand-grip at one limit of its turning movement to close a circuit of the tool, the snap switch having a spring normally tending to move it to circuit-opening position and through said means normally tending to return the handle to initial position.
9. In combination with a tool handle, a hand-grip mounted for rotary movement; an electric switch mounted on the handle and having an actuating member; and a bar fulcrumed on the handle, engaging the actuating member of the switch and connected to the hand-grip to be rocked by the rotary movement of the latter to operate the actuating member of the switch.
10. In combination with a tool handle having a switch housing and spaced arms extending outwardly from the switch housing; a hand-grip mounted in the spaced arms for rotary movement; an electric switch mounted in the switch housing and having an actuating member; and a bar fulcrumed in the

switch housing engaging the actuating member of the switch therein and extending outwardly from the housing in the direction of the forked arms, said bar being connected to the hand-grip for actuation thereby. 70

11. In combination with a tool handle having a switch housing and spaced arms extending outwardly from the switch housing; a hand-grip mounted in the spaced arms for rotary movement; an electric switch mounted in the switch housing and having an actuating member; and a bar fulcrumed in the switch housing engaging the actuating member of the switch therein and extending outwardly from the housing in the direction of the forked arms, said bar having an end engaging a notch in the hand-grip for actuation by rotation of the hand-grip. 75

12. In combination with a tool handle having a switch housing and spaced arms extending outwardly from the switch housing; a hand-grip mounted in the spaced arms for rotary movement; an electric switch mounted in the switch housing and having an actuating member; and a bar fulcrumed in the switch housing engaging the actuating member of the switch therein and extending outwardly from the housing in the direction of the forked arms, said bar having a pair of arms extending in the direction of the spaced arms on the handle and having their ends extending into notches in the handle so that the bar will be depressed by rotation of the handle. 80

13. In combination with a tool handle, a tool-directing hand-grip mounted for turning movement within limits; a switch actuated by the hand-grip at one limit of its turning movement to close a circuit of the tool; and means interconnecting the hand-grip and the switch permitting turning movement of the handle incidental to movements of the operator's hand in manipulating the tool without causing the switch to open the circuit of the tool. 95

14. In combination with a tool handle, a hand-grip mounted for turning movement; an electric switch for controlling a circuit; actuating means for said switch; means interconnecting the hand-grip and actuating mechanism of the switch for operation of the latter by the former when the grip is turned by hand to close the circuit; and means in said switch for normally urging the switch-actuating mechanism and the interconnected hand-grip toward circuit opening position. 110

Signed at Stratford, in the county of Fairfield, and State of Connecticut, this 24th day of November, 1930.

ARTHUR C. GAYNOR. 115
